UNITED STATES PATENT OFFICE.

CHARLES A. NELSON, OF UTICA, NEW YORK, ASSIGNOR TO SAVAGE ARMS CORPORATION, OF UTICA, NEW YORK, A CORPORATION OF DELAWARE.

FIREARM.

Application filed March 25, 1920. Serial No. 368,501.

To all whom it may concern:

Be it known that I, CHARLES A. NELSON, a citizen of the United States of America, residing in the city of Utica, county of Oneida, 5 and State of New York, have invented the following-described Improvements in Firearms.

My invention relates to that type of repeating firearms in which a magazine feeds 10 the cartridges rearwardly into the receiver; and more especially to take-down firearms of this kind in which the barrel and magazine portion is separable from the receiver portion. The object of the invention includes 15 the improvement of the mechanism controlling the passage of cartridges from the magazine to the receiver and their delivery into path of the breech closure and their insertion into the barrel chamber, and certain other improvements which will appear 20 below. To the ends indicated, I provide, in combination, a cartridge cut-off for holding the cartridges in the magazine, a cartridge stop for directing the retreat of the cartridges from the magazine to the cartridge carrier, a cartridge carrier operating mechanism, and a novel co-operation between the cartridge carrier and the said cartridge stop whereby cartridges are readily supplied to 25 and removed from the magazine.

In the accompanying four sheets of drawing which form a part of this specification I have illustrated a take-down repeating shotgun embodying the best form of my invention of which I am now aware.

Fig. 1 is a side elevation of the major part of this firearm. Fig. 2 is an elevation of the portion of the gun adjacent the receiver, partly in section to show the receiver 35 mechanism in breech-closing position. Fig. 40 3 is a similar view showing the mechanism in an initial stage of the opening of the gun. Fig. 4 is a like view (but from the opposite side of the gun) showing the mechanism 45 at a somewhat later stage. Figs. 5, 6 and 7 respectively, show successive positions of the bolt. Fig. 8 is a perspective of the combined action bar retainer and cartridge stop. Fig. 9 is a sectional view showing particularly the left hand side wall of the receiver. Fig. 10 is a plan view of the cartridge carrier and its operating latch. Fig. 11 is a 50 sectional view on the line XI—XI of Fig. 10, looking in the direction of the arrows. Fig. 12 is a sectional view of the receiver 55

and its mechanism on the line XII of Fig. 4, the section of the bolt being omitted. Fig. 13 is a sectional view of the bolt on the line XIII of Fig. 7. Fig. 14 is a sectional view on the line XIV—XIV of Fig. 2. Fig. 15 60 is a perspective view of the cartridge cut-off. Fig. 16 partly in section, illustrates the co-operation between the carrier and the combined action bar retainer and cartridge stop in inserting cartridges in and removing them from the magazine. Fig. 17 is a section on line XVII of Fig. 4.

The barrel 1 carries a barrel clip 2 and an assembly clip 3 which embrace the magazine tube 4 on which the action handle 5 70 slides, the action handle 5 being provided with the rearwardly extending action bar 6; these parts constitute the barrel portion of the gun. The barrel and magazine enter the forward end of the receiver 7 and are 75 adapted for ready attachment thereto and detachment therefrom, while the action bar 6 passes well into the receiver and detachably engages the mechanism therein for actuating the same. The receiver 7 and the 80 stock 8 constitute the receiver portion of the gun for take-down purposes. The exact manner in which the barrel portion is connected to and is removable from the forward end of the receiver portion is immaterial to the present invention and numerous ways in which this may be accomplished are already well-known, it being noted that as a step in the operation of take-down, 85 the action bar 6 must be withdrawn from the receiver 7 prior to the release of the barrel 1 from the receiver. The details of this particular take-down mechanism are disclosed and claimed in a co-pending application of mine. In the receiver, the longitudinally movable breech-bolt 12 is of that common type having a cam slot 13 engaged by a lug 14 on the action bar 6 by which it and the remainder of the mechanism in the receiver are operated; the usual recoil 90 shoulder 15 on the upper surface of the bolt engages in a corresponding notch in the upper wall of the receiver when the gun is locked up. A hammer 18 is pivoted at 95 19 below the bolt 12, and is adapted to strike the firing pin 27 in the usual manner, driving it forward against the pressure of its spring 28. The hammer has a lug 20 on its forward face which is adapted to engage under the rear end of the bolt, to support it 100 105 110

when the action bar lug 14 has been withdrawn from its normal bolt-supporting position in the cam slot. The hammer is actuated by its plunger 24 and spring 25, 5 when released by the trigger 26, and on reaching its forward position carries its presser member 23 into engagement with a part of the action bar lock 21, by which the latter is opened. This action bar lock 21 10 is pivoted at 19 and serves the usual function of obstructing the action bar so as to prevent untimely opening of the gun; its relation to the hammer and the construction of the latter form the subject of a co-pending 15 application. The carrier 22 pivoted at 31 serves to carry cartridges delivered from the magazine 4 into the path of the retracted bolt. The general sequence of operations in guns of this class is briefly as follows: 20 Starting with the mechanism in the position of Fig. 2, the release of the hammer, by pulling the trigger, discharges the cartridge in the chamber, and more or less immediately opens the action bar lock so 25 that the action handle 5 may be moved rearwardly which movement withdraws shoulder 15 from its notch and carries the bolt 12 to the rear to override and again cock the hammer 18. In this movement the empty 30 shell is extracted and ejected through the lateral port shown in Fig. 14, and a fresh cartridge is released and delivered onto the carrier 22 as shown in Fig. 5. In the return movement of the bolt the carrier 22 35 with the cartridge thereon is raised to the dotted line position of Fig. 7 and the advancing bolt pushes the cartridge from the carrier into the chamber. Cartridges are supplied to the magazine through an entrance port in the bottom of the receiver just to the rear of the magazine. 40

According to my invention, I have provided the carrier 22 with an upwardly and rearwardly extending carrier latch 30 mounted 45 in the bifurcated rear end of the carrier 22 and on the same pivot pin 31 as the carrier; the outside arm of this bifurcated end (Fig. 10) is provided in the rear of pin 31, with a transverse lug 32 projecting under 50 latch 30 so that the depression of the latch 30 about its pivot raises the forward end of the carrier (Fig. 7), and the latch 30 can be raised about its pivot without moving of the carrier (Fig. 5). A single spring 35 urges 55 both the latch 30 and the carrier 22 toward their normal positions of Figs. 2 and 6; the straight portion of this spring lies in a slot in the bottom of the receiver (or top of the trigger guard—Figs. 6 and 7) while the end 60 36 is placed under a forward projection from the latch and the end 37 projects upwardly into a notch in the lug 32 of the carrier thus holding the carrier down and the latch against its lug 32. The upper face of carrier 22 is concaved (Figs. 7, 10 and 11) and

toward its rear end the carrier is provided with a transverse shoulder 38 (Fig. 10) to limit the cartridge in its rearward travel on the carrier (Figs. 7 and 11); this shoulder is slotted longitudinally to permit the passage therethrough of the cartridge stop on the bolt later described. The latch 30 is engaged and operated by the breech-bolt during its retreat and forward movement and for this purpose is provided with a lateral 70 projection 40, the underface of which is planar while its upper face is convex and constitutes a cam. The lower part of the side wall 41 of the breech-bolt 12 is provided on its right hand side with an inwardly projecting longitudinally elongated lug 42 (Figs. 5, 6 and 13) so positioned that it engages under the latch projection 40, as the bolt 12 moves to the rear, and thereby raises the latch slightly (Fig. 5) until just prior to the arrival of the bolt at its rearmost position it rides from under the latch allowing it to fall back to normal position against projection 32 of the carrier 22. On the forward movement of the bolt, the lug 42 again engages with the projection 40 but this time it rides on the upper cam surface thereof, depressing the latch 30 accordingly and, through the engagement of the latch with the projection 32, raising the forward end of 95 the carrier (Fig. 7). The new cartridge thereon is thus brought into the path of the bolt in a position to be pushed home by it. As the bolt advances the lug 42 rides off the latch 30 and the carrier and latch are then 100 returned to their normal positions by the spring 35 (Fig. 2).

Delivery of cartridges from the magazine 4 to the cartridge carrier is accomplished by the push of the usual follower 50 and its 105 spring 51 and is controlled by a cartridge cut-off 54 and cartridge stop 55; the former is a spring plate or member mounted in the side wall of the receiver and the cartridge stop 55 is a part of the action bar retainer 110 56 shown in perspective in Fig. 8, and is carried by the bolt. Referring first to the cut-off 54, it will be observed (Figs. 15 and 9) that it comprises a transverse enlargement 115 57 with a tail 58 projecting rearwardly therefrom, both of which parts are fitted snugly into connected cavities 59 and 60 in the left-hand wall of the receiver and thereby held against any movement in the plane of the wall, while the forward flexible end of the cut-off is free to move vertically in the space provided for it. A wall of the trigger guard more or less closes cavities 59 and 60 and retains the cut-off therein. The forward edge of the transversely curved nose 62 of 120 head 61 directly engages the rearmost cartridge in the magazine; a forward projection 63 above the nose occupies an elongated slot 64 beside the rear end of the magazine 125 to assist in holding the cut-off in place, while 130

an upper cam surface 65 engages the action bar 6 which thereby controls the cut-off. The resiliency of the cut-off 54 tends to raise the nose 62 into the path of the cartridges 5 passing from the magazine and also the surface 65 into the path of the rear end of the action bar 6, which is provided with a slot 66 to permit the cut-off nose to rise into the cartridge path when the action bar is re-
 tracted (Figs. 4, 7 and 14). When the action bar is pushed full forward the slot 66 passes beyond the cut-off head and the action bar thus depresses the head 61 so as to move the nose 62 out of engagement with
 the cartridge, and this allows the latter to move rearwardly and into contact with the cartridge stop 55 above referred to. The cartridge remains in this position so long as the gun is locked up. When the action han-
 dle is moved rearwardly to retract the bolt, the cartridge, then abutting against the stop 55, follows that stop to the rear under the influence of the magazine spring and until the cartridge next in rear engages and is stopped by the cut-off which again rises for this purpose as will be understood.
 During the time the cartridge is free of the restraint of the cut-off as thus described, it is under the control of the cartridge stop 30 55 which according to this invention is also a part of the action bar retainer 56 as before indicated. This retainer is a device for retaining the action bar in the receiver so long as the gun is cocked and so that the gun cannot be taken down while it is cocked. It comprises a body portion extending longitudinally of and below the bolt 12 and a vertical plate 67 at its forward end somewhat offset from the body which plate oc-
 40 cupies a recess in the underside of the bolt and is provided with a vertical slot 68 for receiving a transverse pin 69 of the bolt 12. The rear end of the body of 56 rests by its projection 70 on a shoulder on the bolt 12 as indicated in Fig. 2 and the retainer is urged downwardly by a spring 71 which normally presses the upper end of the slot 68 against the pin 69 and the projection 70 against its shoulder. In this position of
 45 the retainer a shoulder 72 thereon occupies a position in front of the forward end of the slot 13 in the side wall of the bolt so that the action bar lug 14 cannot be withdrawn from said slot without encountering it and pushing it out of the way. The action bar is not required to leave the bolt slot except when the gun is to be taken down and on such occasions it must push the retainer shoulder upwardly in order to
 50 escape. A pin 74 in the upper side of the retainer is adapted to register with and enter a notch 73 in the firing pin when the latter is pressed forwardly by the hammer to accommodate such movement, but when
 55 the firing pin is not forward, it blocks the
 retainer and thereby blocks removal of the action bar lug from the bolt. Accordingly it follows, that the action bar 6 can be withdrawn from bolt and the receiver, and the gun taken down, only when the firing means 70 is in its fired position and it follows from this that there can be no explosion of the cartridge in the barrel in the midst of take-down by the accidental fall of these means. This function of retainer 56 is disclosed and 75 claimed in a co-pending application of mine. The present invention concerns the double use of this retainer as a cartridge stop as before indicated, and it will be obvious that the precise form and manner of opera- 80 tion of the retainer as a means for preventing escape of the action bar lug are not important to its cartridge stopping function. It may be variously located and still perform both functions as will now be ap- 85 parent. As above stated the cartridge engages the stop 55 when released by the cut-off and continues to the rear with it and the bolt until it strikes the shoulder 38 on the carrier 22 (see Figs. 5, 6 and 7) and 90 preferably the bolt 12 retreats until 55 passes somewhat to the rear of 38, and the lifting of the carrier is so timed that it is well elevated by the time the stop 55 again passes the shoulder 38, so that when the bolt engages the cartridge to push it forward from the carrier, the cartridge is 95 already pointed toward the open chamber. The longitudinal slot in shoulder 38 provides clearance for the stop 55 to pass 100 through it in accomplishing this action. As before pointed out, the carrier returns to its lower position as the bolt is seated, and at about the same time the cam surface 65 of the cut-off is again engaged by the action bar 6, the head 61 depressed, and the control of the cartridges remaining in the magazine given back to the stop 55 (Fig. 2).
 To charge or discharge the magazine of cartridges it is only necessary (the breech-bolt and action bar being forward) to manually raise the carrier 22 from the cartridge entrance port in the base of the receiver and raise the cartridge stop 55 (against spring 71) out of the path of the cartridges in the magazine (Fig. 16); the carrier can be raised manually and is of sufficient length to engage and raise 55 so that all that is required to empty the magazine is to press the carrier upwards. With the cartridge carrier so elevated, cartridges may be pushed into the magazine, and as the last cartridge is inserted and the carrier 22 allowed to fall stop 55 simultaneously falls 110 and the last cartridge assumes its desired 115 position against the latter. When cartridges are thus fed to the magazine or removed therefrom, the retainer and stop 56 pivots about projection 70 and its co-operating shoulder; the upward projection 74 may be 120 125 130

short enough to allow this movement even with the hammer cocked and notch 73 displaced to the rear of the projection, or may be so long as to require that the hammer be down (against the breech-bolt), as desired.

Besides the mechanism described, the drawings also disclose certain other related mechanism; 80 is a pivot or stud projecting inwardly from the left hand wall of 10 the receiver to support the forward end of the bolt; the forward end of the bolt 12 engages with this stud 80 as it reaches its foremost position and fulcrums on it as it swings upwardly to engage the shoulder 15 notch in the receiver. This matter is also disclosed and claimed in a co-pending application. The trigger 26 is pivoted at 81 in the trigger guard and adjacent its rear end is provided with an ear 82 against 20 which the lower end of the trigger plunger 83 thrusts, such plunger being bifurcated to straddle the hammer plunger 24. The trigger plunger 83 is surrounded by the trigger spring 84 and a safety 85, provided 25 with a spring detent 86, is adapted to be moved into and out of blocking position at the upper end of the trigger plunger 83, as will be apparent from the drawing. It may be noted that the safety 85 acts as an 30 indicator of the position of the hammer for when the hammer is against the breech-bolt the rear end of the trigger and its plunger 83 are elevated, and accordingly the safety 85 cannot be moved from its forward position 35 which constitutes the indication.

Extractors 87 at opposite sides of the bolt withdraw exploded shells from the barrel, the left hand extractor riding in slot 88 in the receiver wall and the righthand extractor 40 traversing the side ejection port and an interior slot to the rear of the same as the bolt moves rearwardly. As the bolt approaches its rearmost position a forward shoulder of ejector 89 lying in cavity 90 of 45 the lefthand receiver wall projects in front of the bolt (Fig. 6) and ejects the cartridge or empty shell through the side port in the opposite receiver wall.

While I have thus illustrated and 50 described in some detail the best embodiment of my invention of which I am now aware, it will be understood that the same is illustrative and that my invention is not limited thereto except as definitely specified in the 55 following claims:

Claims.

1. A take-down, repeating firearm comprising in combination, a breech-bolt, an action bar removably engaged with the 60 breech-bolt, a cartridge magazine and a member serving the double function of locking the action bar to the breech-bolt and controlling the delivery of cartridges from the magazine.

65 2. A take-down, repeating firearm com-

prising a receiver, a breech bolt, firing means, an action bar provided with a lug to engage a slot in the bolt, a cartridge magazine, and a combined action bar retainer and cartridge stop consisting of a member carried by the breech-bolt and provided with one part to obstruct escape of the action bar lug from its slot and another part to control the delivery of cartridges from the magazine, said combined retainer and stop being controlled by the condition of the firing means.

3. A repeating firearm comprising a receiver, a magazine adapted to feed cartridges rearwardly into the receiver through its forward end, the receiver being open at the bottom to allow the charge and discharge of the magazine therethrough, a breech-bolt, a carrier pivoted in the receiver to the rear of said opening and normally closing the same, a cartridge cut-off to hold the cartridges in the magazine when the breech-bolt is open, and a movable cartridge stop on and depending from the breech-bolt, the said carrier being adapted to engage the cartridge stop to displace the same out of cartridge stopping position when the carrier is moved inwardly and the breech-bolt is closed.

4. A repeating firearm comprising a receiver, a magazine adapted to feed cartridges rearwardly into the forward end of the receiver, a carrier in the receiver, an action bar sliding longitudinally for re-loading, a breech-bolt operated thereby, a cartridge stop on the forward end of the breech-bolt for holding the cartridges in the magazine and against which the cartridges abut as they are fed from the magazine and whereby they are seated on the carrier only as the breech-bolt retreats, and a cartridge cut-off, said action bar depressing said cut-off from its operative position when the bolt is locked up and rendering the cut-off operative when the bolt is moved to the rear of such position, the carrier having a shoulder to stop the rearward movement of the cartridge thereon before the breech-bolt reaches its rearmost position.

5. A repeating firearm comprising a receiver, a magazine adapted to feed cartridges rearwardly into the receiver, and a cartridge cut-off comprising a resilient member fitted in part in a closely-enclosing cavity in the receiver wall, the walls of the cavity thereby restraining the movement of said part of the cut-off so that the latter bends as it operates to engage and release the cartridges.

6. A repeating firearm comprising a receiver, a magazine adapted to feed cartridges rearwardly into the receiver, a cartridge cut-off, said cut-off comprising a resilient member seated in part in a closely-enclosing cavity in the receiver wall, the walls of the cavity

70

ity thereby restraining the movement of said part of the cut-off so that the latter bends as it operates to engage and release the cartridges, a trigger guard extending over the opening of said cavity and thereby confining the cut-off therein, and means in the receiver to operate the cut-off against its resiliency.

7. A repeating fire arm comprising a receiver, mechanism therein, a magazine to feed cartridges to the receiver, a resilient cartridge cut-off to retain cartridges in the magazine, the cut-off being seated in a cavity in the receiver and extended forward from such seat to adjacent the magazine opening and being operable in one direction by said mechanism against its resiliency, and means closing said cavity to hold the cut-off in position.

8. The combination in a repeating fire arm, of a receiver, a cartridge cut-off comprising a resilient bar provided with a cartridge engaging head movable in the receiver, the end of said cut-off opposite said head being seated in a cavity in the receiver restraining movement of said opposite end, and means closing said cavity.

9. The combination in a repeating fire arm, of a receiver, a spring yielding cartridge cut-off having a forwardly facing shoulder adjacent its rear end by which it is immovably seated in a cavity in the receiver wall, its other end being free to move parallel with said wall.

10. The combination in a repeating fire arm, of a receiver and a cartridge cut-off comprising a resilient bar adapted at one end to movably engage cartridges and loosely seated at its opposite end in a cavity in the receiver, the walls of said cavity preventing the displacement of the cut-off and restraining movement of said opposite end.

11. A repeating firearm comprising carrier mechanism and mechanism longitudinally movable to reload the arm, characterized by said longitudinal mechanism and carrier mechanism being provided with cooperating projections for operating the carrier, one projection being movable with respect to the part carrying it and both being arranged so that faces of said projections are engaged on the rearward movement of said longitudinal mechanism which are opposite the faces of said projections which are engaged on the forward movement of said longitudinally movable mechanism.

12. A repeating firearm comprising a longitudinally movable breech-bolt and a carrier, characterized by the breech-bolt and carrier carrying a relatively movable latch and a cooperating projection for operating the carrier whereby the projection engages along one side of the latch in the rearward movement of the breech-bolt and along the

opposite side of the latch in the forward movement of the breech-bolt.

13. A repeating firearm comprising a longitudinally movable breech-bolt and a carrier, characterized by the breech-bolt being provided with a lateral projection from a wall thereof, a cooperating lateral projection from the carrier to operate the latter, and one of said projections being movable with respect to the part carrying the same whereby the breech-bolt projection rides over the carrier projection when the breech-bolt is moved in one direction and rides under the carrier projection when the breech-bolt moves in the opposite direction.

14. A repeating firearm comprising a longitudinally movable breech-bolt, a pivoted carrier, and a pivoted carrier latch provided with a lateral projection, the latch being disposed between the carrier ends and being adapted to engage and elevate the carrier as the latch is depressed, the breech-bolt being provided with a lateral projection to engage under the latch projection and elevate the latch as the breech-bolt moves to the rear and to ride over the latch projection and depress the latch as the breech-bolt returns forward.

15. A repeating firearm comprising a receiver, a longitudinally movable breech-bolt, a pivoted carrier and a carrier latch pivoted co-axially with the carrier and adapted to engage said carrier to elevate the same as the carrier latch is moved in one direction, and to move in the other direction without actuating the carrier, the breech-bolt and carrier latch being provided with cooperating surfaces to operate the carrier latch in the two directions alternately to elevate the carrier.

16. In a repeating firearm, the combination of a compound movement breech closure, a depressible cartridge stop thereon, and a cartridge carrier having a cartridge stopping shoulder notched to permit the passage of said cartridge stop thereby the carrier being adapted to depress said cartridge stop from its cartridge stopping position.

17. In a repeating firearm, the combination with a compound movement breech closure, a pivoted cartridge carrier, and a vertically movable latch adjacent one of the first mentioned two parts adapted to pass under and over the other of said two parts as the breech closure retreats and advances, to elevate the carrier.

18. In a repeating firearm, the combination with a compound movement breech closure, a pivoted cartridge carrier, and a vertically movable latch adjacent one of the first mentioned two parts and provided with a lateral projection, the other of said two parts being provided with a cooperating lateral projection, one of said projections

being arranged to pass over the other as the breech closure retreats and to pass under it as the closure advances, to elevate the carrier.

- 5 19. In a repeating firearm in which the cartridges are fed rearwardly from the magazine into the receiver, the combination of a longitudinally movable breech-bolt, a longitudinally sliding action bar for opening and closing the bolt, a cartridge cut-off to prevent the feeding of cartridges, said cut-off being controlled by one of said longitudinally movable members to release the cartridges when the breech-bolt is closed, a cartridge carrier, and a cartridge stop on and depending from the breech-bolt, said carrier when raised manually engaging and displacing the cartridge stop from cartridge stopping position.
- 10 20. In a repeating firearm in which the cartridges are fed rearwardly from the magazine into the receiver, the combination of a longitudinally movable breech-bolt, a longitudinally sliding action bar for opening and closing the bolt, a cartridge cut-off to prevent the feeding of cartridges from the magazine, said action bar depressing the cut-off to release the cartridges in the magazine when the breech-bolt is closed, an entrance 15 part for the cartridges, a pivoted cartridge carrier, and a cartridge stop on and depending from the breech-bolt and engageable by the carrier to release the cartridges and permit their discharge from the firearm.
- 25 21. In a repeating firearm in which the cartridges are fed rearwardly from the magazine into the receiver, the combination of a longitudinally movable breech-bolt, a longitudinally sliding action bar for opening and closing the bolt, a cartridge cut-off to prevent the feeding of cartridges, said cut-off being controlled by one of said longitudinally movable members to release the cartridges when the breech-bolt is closed, a cartridge entrance port, a cartridge carrier, and a double function member to control the withdrawal of the action bar and to stop and control the feeding of cartridges, said carrier being operable manually to displace 30 said double function member from cartridge stopping position to permit the discharge of said cartridges through said entrance port.
- 35 22. In a repeating firearm, the combination of longitudinally movable breech opening and closing mechanism, and a pivoted cartridge carrier, said parts having cooperating carrier operating members one of which has a cammed generally-horizontal surface and one of which is movable vertically with respect to the part which carries it, said cammed surface being engaged by the other of said members when the breech mechanism is moving in one longitudinal direction to elevate the carrier, the generally- 40 horizontal surface opposite said cammed sur-

face being engaged by said other of said members when the breech mechanism is moving in the opposite longitudinal direction.

23. In a repeating firearm, the combination of a sliding breech-bolt, an action bar 70 actuating the same, a pivoted cartridge carrier which is depressed when the breech-bolt is closed, a laterally projecting member on the carrier, one generally-horizontal surface of which is cammed, and a laterally projecting member on the breech-bolt, one of said laterally projecting members being movable in a vertical plane with respect to the part which carries it, and the member on the breech-bolt passing along the generally-horizontal surface of the member on the carrier which is opposite said cammed surface, when the breech-bolt is moved to the rear and traveling on the said cammed surface when the breech-bolt is moved forward, 80 thereby elevating the carrier.

24. In a repeating firearm, the combination of a compound movement breech-bolt, a sliding action bar for actuating the same, a pivoted carrier which is depressed when the breech-bolt is closed, a laterally projecting member at the rear of the breech-bolt, and a cooperating lateral projection on the carrier at the rear of its pivot, the upper 90 face of the last mentioned member being 95 cammed and one of said members being movable vertically, by the engagement of the two, with respect to the part which carries it, so that the member on the breech-bolt passes underneath the member on the carrier when the breech-bolt moves to the rear and passes over said cammed face when the breech-bolt moves forward, thereby elevating the carrier.

25. In a repeating firearm, a cartridge cut-off comprising a resilient bar-like member having an enlargement adjacent one end thereof which is fitted into a cavity snugly confining the bar adjacent said enlargement and holding the cut-off in place, the cut-off being arranged to engage the cartridges adjacent its opposite end which is movable into and out of cartridge engaging position, and means for moving said cut-off to one position against its resiliency.

26. In a repeating firearm in which the cartridges are fed rearwardly from the magazine, the combination of the receiver, reloading mechanism therein, and a resilient cut-off comprising a resilient bar-like member arranged to engage the cartridges adjacent its forward end and having an enlargement near its rear end, said enlargement being seated in a snugly confining cavity in the receiver which thereby retains said rear end of the cut-off in position while the forward end of the cut-off moves to and from its cartridge engaging and cartridge releasing positions, said reloading mechanism actuating the forward end of the cut-off to 125 130

one of said positions and the resiliency of the cut-off returning it to the other of said positions.

27. In a repeating firearm in which the cartridges are fed rearwardly from the magazine, the combination of the receiver, a longitudinally movable breech-bolt therein, an action bar for moving said bolt, a resilient cartridge cut-off the rear end of which is fitted snugly into a cavity in the side wall of the receiver, and a removable trigger guard extending over said cavity to prevent the escape of the cut-off from the cavity, the forward end of the cut-off being movable into and out of cartridge engaging position and the action bar engaging said forward end of the cut-off and being recessed so that the action bar moves said forward end of the cut-off to one of its positions against its resiliency and the resiliency of the cut-off returns the forward end of the cut-off when said recess is opposite the same.

28. In a takedown repeating firearm, the

combination of a receiver, a longitudinally movable breech-bolt therein, a sliding action bar having a projection extending into a slot in one side of the breech-bolt and from which the projection is withdrawn to take down the gun, a magazine feeding cartridges rearwardly into the receiver, and a combined action bar lock and cartridge stop comprising a single member having a portion pendant from the centerline of the breech-bolt to control the feeding of the cartridges from the magazine and a portion arranged at the slot side of the bolt to obstruct the escape of the action bar from the breech-bolt slot, each of said portions of the single member being independently operable so that the release of the cartridges and the release of the action bar are independently controllable.

In testimony whereof, I have signed this specification.

CHARLES A. NELSON.
